UNITED STATES PATENT OFFICE.

PHILIP A. KOEHRING, OF MILWAUKEE, WISCONSIN, ASSIGNOR TO KOEHRING MACHINE COMPANY, OF MILWAUKEE, WISCONSIN.

CHARGING DEVICE FOR CONCRETE-MIXERS.

1,107,171.

Specification of Letters Patent.

Patented Aug. 11, 1914.

Application filed September 9, 1913. Serial No. 788,918.

To all whom it may concern:

Be it known that I, PHILIP A. KOEHRING, a citizen of the United States, residing at Milwaukee, in the county of Milwaukee and State of Wisconsin, have invented certain new and useful Improvements in Charging Devices for Concrete-Mixers, of which the following is a specification.

This invention relates to the type of concrete mixing machines wherein a suitable mixing drum is mounted upon a truck or equivalent support and disposed within a framework erected adjacent thereto on said support, and which framework carries certain hoisting mechanism operable by a motor and connected with a charging device for the mixing drum preferably in the form of a movably mounted bucket.

The object of the invention has been to devise a special form of charging device, the same comprising a bucket pivotally mounted upon the framework above mentioned in a peculiar manner so as to permit of using a much lower framework than has heretofore been required in similar machines, as well as affording a greater leverage for the hoisting means in lifting the load of materials received by the bucket to be subsequently discharged therefrom into the mixing drum.

The invention comprises certain other detail features of construction that will be more fully set forth hereinafter and fully understood on reference to the accompanying drawings in which,

Figure 1 is a side elevation of a mixing machine, showing the present invention applied thereto. Fig. 2 is an end view of the machine, looking toward the inlet of the mixing drum, certain parts of the hoisting mechanism, and the charging bucket being omitted.

In the drawings, A denotes a truck which comprises suitable ground wheels B and is adapted to be moved over the ground by power transmitted from a suitable motor supported on the truck, or by draft means, if desired. The truck A carries the mixing drum C which may be of any conventional type, being illustrated as gear driven, and having a suitable inlet 1 and outlet 2. The drum C is located within a framework erected on the truck A and comprising end uprights 3 and 4, intermediate uprights 5, the upper longitudinal bars 6, and the cross

bars 7, which connect the members 6 together at points adjacent to the uprights 3 and 5; the uprights 4 not being connected by any such cross bars 7, since it is desired that the framework at the charging end of the machine be open for a purpose herein-after described. Mounted in suitable brackets carried by the intermediate uprights 5 is a winding shaft 8 on which are mounted the drums 9 of like form, and 65 the drum 10 of considerably larger diameter than the drums 9. A main operating cable 11 is connected with the drum 10, and with an actuating drum 12 supported by a drive shaft 13 seen in Fig. 1 as 70 directly supported by the truck A, and adapted to be operated from the motor D, supported by said truck. Cables 14 connect the drums 9 with the opposite sides of the charging device or bucket 15 75 which is located at the front end of the machine and is of angular form, as illustrated in Fig. 1. Intermediate the ends of the upper portion of the bucket 15, said bucket has secured thereto pivot arms 16, 80 the free innermost ends of which have as an axis a shaft 17 which is supported by inclined bars 18 which connect and brace the uprights 4 and 5. The point of connection of the arms 16 with the bucket 15 being offset from the delivery end of the bucket adjacent thereto, permits this end to partially enter a trough 19 when the bucket is raised in the dotted line position shown in Fig. 1 for discharging its contents into the 85 mixing drum C. The trough 19 will be fixedly mounted upon the framework in any suitable manner with its lower end partially introduced into the inlet end of the drum C, and its upper end partly supported 90 by a cross piece 20 on the bars 18.

Having in view the fact that the uprights 4 are spaced apart so as to permit the bucket 15 to operate therebetween, and the further fact that the upper ends of said uprights 100 are not directly connected together, it will be apparent that in the operation of raising the bucket 15, by means of cables 11 and 14 and the driving means therefor, said bucket is adapted to move at its outer end between 105 the adjacent ends of the horizontal bars 6 of the framework aforesaid. Under these conditions the sheaves 21 over which the cables 14 pass may be located in a comparatively low position, and the arrangement 110

of said sheaves and the point of pivotal support of the bucket 15 permits of elevation of the bucket 15, to its discharging position by the exercise of a minimum amount of 5 power. The raising and lowering of the bucket 15 is, of course, accomplished by reverse movement of the drum 10 and the operation of certain controlling mechanism that does not form any part of the present 10 invention.

Having thus described my invention, what I claim as new is:

1. In means of the class described, the combination of a support, a framework 15 erected thereon and comprising a plurality of spaced uprights, bars connecting said uprights at their upper ends, inclined connecting and brace bars intermediate certain 20 of said uprights of the framework, a charging bucket comprising an outer receiving portion and an inner delivery portion, pivot arms secured to the bucket at the delivery portion thereof and supported by said inclined brace bars, hoisting means including 25 cables connected with the receiving portion of the bucket and movable to raise said receiving portion into a discharging position in which it enters the space between the upper horizontal bars of the framework, and 30 sheaves on the framework over which said cables pass.

2. In means of the class described, the

combination of a supporting truck, a framework 35 work thereon consisting of spaced sides; each side composed of a plurality of uprights, upper horizontal bars connecting the upper ends of the uprights of each side of the framework, cross bars connecting said horizontal bars at one end and intermediate 40 the ends of the framework, the other end of the framework being open at its upper end, inclined brace bars connecting certain uprights of each side of the framework, a pivot shaft supported by said inclined 45 brace bars, charging means including a bucket comprising a receiving portion and a discharging portion; pivot arms projecting from the discharging portion of said bucket intermediate its ends and connected with the pivot shaft aforesaid, sheaves on 50 the upper portion of the framework at one end of the same, and hoisting means including cables passing over said sheaves and connected with the receiving portion of said bucket to raise the latter into a position in 55 which said receiving portion enters the space between the sides of the framework at the open end of the latter.

In testimony whereof I affix my signature in presence of two witnesses.

PHILIP A. KOEHRING.
